NON-THUMB-SUCKING GARMENT AND
METHOD OF MAKING THE SAME

Johanna Bommer, Greenwich, Conn.

Application October 7, 1938, Serial No. 233,839

2 Claims. (Cl. 128—136)

The present invention relates to an infant's non-thumb-sucking garment and the method of making the same.

An object of the invention is to provide a novel and improved garment which is especially adapted for use in connection with preventive dentistry, as the use thereof prevents the infant from sucking the digits of the hands, and more particularly the thumb. This sucking habit, if allowed to continue, invariably pulls the lower jaw forward, resulting in a facial deformity caused by the excessive unidirectional pressure upon the infant's jaw bone during the formative period thereof.

Another object is to provide an easily-washable hand and arm covering made of linen or the like, which is worn by an infant to prevent thumb sucking.

Another object is to provide a non-thumb-sucking garment which is particularly adaptable for use by the infant who is teething during the excessively warm summer months.

A further object is to provide a non-thumb-sucking garment which prevents a child user from directly touching its arms or hands.

Another object is to provide an easily-washable, economical non-thumb-sucking garment which is made from one piece of linen or the like, in such a manner as to reduce the number of seams to a minimum, thus decreasing the cost of making each article and eliminating seams which irritate the skin of the infant when it constantly comes in contact therewith.

Another object is to provide a flexible non-thumb-sucking garment freely covering the arms and hands of the infant user and removably fastened around its neck, whereby the child is unhampered in the movement of its arms and hands but refrains from sucking its thumb or fingers because of the uninviting feeling in his mouth of the flexible casing thereabouts or because of the width of the casing is unable to find its thumb.

Another object is to provide a cool, neat, sanitary and comfortable non-thumb-sucking garment particularly to be used by the summer babies, i. e., those which teethe during the hot summer months, at which time they are prone to acquire the undesirable and injurious thumb sucking habit.

Another object is to provide a non-thumb-sucking garment which is adapted to be worn over an infant's dress or coat or to be worn directly in contact with the child's body.

Another object is to provide an easily washable and easily drible non-thumb-sucking garment of

such a width and length throughout the arm and hand portions thereof as to give the infant complete comfort and freedom of movement, and of such a flexibility as to allow the infant to grasp the side walls of its crib for support as it toddles about.

Other objects and advantages of this invention will be apparent from the following specification and from the claims appended hereto.

In the drawing wherein like numerals refer to like or corresponding parts throughout the several views,

Figure 1 is a plan view of an integral blank of linen or the like, from which the non-thumb-sucking garment is made,

Figure 2 is a front elevation of the garment in its completed form,

Figure 3 is a view taken along the lines 3—3 of Figure 2,

Figure 4 is a sectional view taken along the lines 4—4 of Figure 2, and

Figure 5 is a modification fragmentarily showing a collar piece stitchedly engaging the wing members.

Referring now to the drawing, the numeral 10 indicates generally a blank of linen or any other flexible material. The blank 10 comprises two wing members 11 and 12. The wing member 11 is provided with flat edges 13 and with rounded edges 14 which are an integral continuation of the flat edges 13 in a direction substantially right angular. The rounded edges 14 converge inwardly at the inner end portions thereof and meet in a common point 15. The edges 16 are an integral continuation of the edges 13 and extend inwardly therefrom at an angle. Each of edges 16 at the inner ends thereof are integrally connected with a neck or collar portion 17 which is provided with free ends 18. Adjacent the free ends 18 are the buttons 18b which are proportioned to removably engage through the button holes 18a. Any other fastening means may be used if so desired, e. g., a zipper adapted to open so as to allow the garment to be removed over the infant's head.

The wing member 12 is provided, in a manner corresponding to wing member 11, with flat edges 19 and rounded edges 20 which terminate at a common point 21. The edges 22 extend inwardly from and are an integral continuation of the edges 19. At their inner ends the edges 22 merge into the collar portion 17 at a point oppositely spaced from the points at which edges 16 merge into the said collar portion.

In forming the non-thumb-sucking garment from the blank 10 the flat edges 13 and 19 and

the rounded edge portions 14 and 20 of the wing members 11 and 12 respectively are brought into abutting position and sewed or otherwise fastened together. The stitching runs along the edges 13 and 14 of the wing member 11 and terminates at the point 15, and in wing member 12 it runs along the edges 19 and 20 and terminates at the point 21, to thereby completely close the outer end and side portions of the wing members 11 and 12 respectively. The edges 16 are not fastened together and thereby form an opening at the upper end of the wing member 11 which is adapted to comfortably receive therein the hand and arm of an infant. Likewise, the edges 22, in their unfastened condition, furnish an opening at the upper end of the wing member 12 which is proportioned to receive the other hand and arm of the infant user.

In Figure 5 of the drawing, 11a designates a wing member stitchedly or otherwise fastened to a collar portion 17a. At a point diametrically opposite to the area of jointure of the wing 11a to the collar portion 17a is a similar wing member 12a which is similarly attached to the said collar portion. In this modification of the invention, the completed non-thumb-sucking garment is formed from three pieces, the collar portion 17a and the two wing members 11a and 12a attached thereto. The collar portion 17a is adapted to be disposed around the neck of the infant user and fastened together by engaging the buttons 18b through the button holes 18a, or in any other manner. The collar portion 17a when it is fitted around the neck of the child user, rests flatly upon the shoulder blades and thus supports the garment and keeps the wing members 11a and 12a from sliding down and exposing the arms and hands. The collar portion 17a fits loosely about the child's neck and there is no danger of choking.

The wing members 11 and 12 are each greater in length than the combined length of the infant's hands and arms which they are adapted to receive. The width of the said wing members 11 and 12 is substantially greater than the width of the infant's arm. This greater length and width of the flexible wing members 11 and 12 respectively permits the infant to freely work its arms and hands therein and at the same time decrease the chance of the infant finding its thumb or fingers when it is beset with the desire so to do. The wing members 11 and 12 have respectively unseamed portions 23 and 24 which

normally contact the infant's arms when the garment is worn. These seamless areas of body contact eliminate any chafing or irritation of the infant's tender skin which would result if the infant's arms rubbed continuously against a 5 seamed area.

The seams along the edges 13, 14, 19 and 20 are preferably so constructed so that the jointures will be interiorly free from any rough spots which might cause irritation of the infant's skin. At 10 the same time the seam areas are of such a structure that the complete non-thumb-sucking garment presents a neat and attractive appearance.

When in use the wing member 11 encases the infant's right arm and hand and the wing member 12 covers the left arm and hand. The collar portion 17 rests upon the infant's shoulders and is comfortably fastened around its neck. The wing members are thus prevented from sliding down and exposing the infant's hands. This feature combined with the exaggerated length and width of the said flexible wing members provides an effective non-thumb-sucking garment.

Further modifications will be apparent to those skilled in the art and it is desired, therefore, that the invention be limited only by the prior art and the scope of the appended claims.

Having thus fully described my invention, what I claim and desire to secure by Letters Patent is:

1. A flexible cloth blank for use in making a 30 non-thumb-sucking garment which comprises, a pair of diametrically opposed portions, each of said portions having a pair of substantially parallel side edges merging at one end thereof into rounded outer edges and at the other end into 35 inwardly extending inner edges, and said inner edges merging into an intermediate portion connecting said diametrically opposed portions.

2. A flexible cloth blank for use in making a 40 non-thumb-sucking garment which comprises, a pair of diametrically opposed portions, each of said portions having a pair of oppositely disposed substantially parallel side edges merging at the outer ends thereof into rounded edges which terminate at a common point intermediate said parallel edges, each of said parallel side edges merging at the inner ends thereof into inwardly extending edges which merge into a substantially 45 circular portion centrally recessed, and said circular portion connecting said diametrically opposed portions.

JOHANNA BOMMER.
